TYPEWRITING MACHINE

William F. Helmond, Clinton, Conn., assignor to
Underwood Elliott Fisher Company, New York,
N. Y., a corporation of Delaware

Application December 3, 1941, Serial No. 421,405

13 Claims. (Cl. 197—186)

This invention relates to typewriting machines and, more particularly, to composite masking structures for such machines or portions thereof.

Although composite masks are well known in the art, their construction is usually such that it is awkward or inconvenient to remove or assemble the component sections on the machine. Also composite masks often are unstable in construction and invariably the component masking sections are held together by exposed, unsightly fastening devices reducing the attractiveness and salability of the machine.

It is an object of the invention to provide a knock-down composite mask which is assemblable on the machine with ease and speed, yet which, when assembled, has virtually the strength and ruggedness of a unitarily constructed mask.

It is a further object of the instant invention to provide an efficiently assemblable composite mask, the assembled structure of which does not reveal the means by which the mask is held together and fastened to the machine.

Another object of the invention is to so construct a composite mask that at least certain component portions thereof are conveniently displaceable and/or removable to gain access to certain mechanisms normally covered thereby.

It is also an object of the invention to provide an assembled mask which, although quickly and conveniently assembled upon the machine, will not rattle.

Additional objects and features of the novel mask structure will become apparent from the drawing, particularly when the drawing is read in the light of the description and the appended claims.

The invention is shown as it may be applied to the carriage of a typewriting machine, but it should be understood that the invention is applicable to any other portion or portions of such machines, particularly also to main bodies thereof.

In the accompanying drawing:

Figure 1 is a rear perspective view of a typewriter carriage having the composite mask of the invention applied thereto.

Figure 2 is a fractional rear view of the right end of the carriage seen in Figure 1.

Figure 3 is a right end view of the carriage including fractional portions of the composite mask.

Figure 4 shows a left end view of the carriage with an end cover thereon.

Figure 5 is a sectional front perspective view

showing an interlocking joint between two masking sections.

As hereinbefore pointed out, the invention is shown applied to a typewriter carriage. This carriage may comprise a mechanism-supporting frame 11 having upright, opposite carriage end plates 12 connected to the opposite ends of a carriage rail or bar 13. See Figure 3. The rail 13, and consequently the carriage frame 11, is guided in a conventional manner for letter-feeding and return movements upon a trackway 14 comprising a part of the main framework of the machine. A platen 15, together with its rotating knobs 16, is preferably removably mounted on the carriage frame. The carriage end plates 12, for this purpose, may be notched as at 17 to provide mounting seats for the platen. The platen may be removably retained in said seats by means disclosed in the patent to Helmond No. 2,172,008, dated September 5, 1939.

The composite mask for the carriage comprises two oppositely disposed side covers or masking members 18 and an intermediate masking member or shroud 21. These spaced members 18 have inwardly extending top and rear flanges 22 and 23, respectively, and constitute therewith narrow housings flanking the carriage end plates 12 and such mechanism as may be supported in adjacency thereto. Each of the side covers 18 is removably seatable on the frame ends 12, and to this end they are at their inner sides provided with brackets 24 having inwardly extending forked front and rear ears 25 and 26, respectively. These forked ears fit over front and rear pins 27 and 28, respectively, the pins being carried by laterally projecting lugs 31 on the end plates 12 of the carriage. The forked ears 25, 26 and the associated pins 27, 28 are so disposed that the side covers 18 may be swung toward or away from each other, to and from masking position. Also, by reason of the forked ears, the covers 18 are readily attachable or detachable from the machine. The frame lugs 31 are so located as to cooperate with the forked ears 25 and 26 to locate the masking members 18 in a fore-and-aft direction on the carriage.

The intermediate shroud or member 21 may consist of a rear wall 32 merging into a forwardly extending top wall 33. The spaced masking members or covers 18 and the intermediate shroud have respectively inwardly-reaching rims 34, 35 facing each other so as to provide substantial abutting surfaces. On the opposite ends of the intermediate member 21, near the bottom 55 of the rear wall 32, the rims 35 are extended for

wardly to form open pivot seats 36 normally resting on pivot studs or pins 37. These pins extend toward each other from the rear portions of the side covers 18, each pin being preferably supported on an ear 38 bent from one of the forked ears 26. From this it will be seen that the shroud 21 is pivotally displaceable about the said pivot studs 37, to and from masking position; or may be, if desired, entirely removed from the machine. Means are provided whereby in moving the shroud 21 to masking position, the covers or members 18 become firmly interlocked with the shroud in the direction in which the covers are spaced. More specifically, each of the side covers 18 has, near its upper rear portion, a groove-forming protuberance or ear 41 into which one of the inwardly extending rims 35 of the shroud 21 fits. It may be said that the protuberances 41 and the rims 35 fitting therein constitute tongue-and-groove joints. The ears 41 are so disposed and formed that the shroud 21 is movable to and from masking position. In some cases, it may be desirable to provide a tongue-and-groove interlock along the entire adjoining edges of the composite masking members 18 and 21.

The means by which the composite mask is held assembled upon the carriage will now be described. Upon each carriage end plate 12 is pivoted a rearwardly extending arm 42 having a rearwardly inclined camming ear 43. Strong springs 44 which are anchored on the end plates 12 of the carriage, draw the arms downwardly. The ears 43 overlie tongues 45 reaching forwardly and upwardly from the shroud rims 35, and act thereupon to urge the shroud 21 forwardly as well as downwardly. The result is that the shroud is seated and forced firmly onto the pins 37 of the side covers 18 and against the bottom of the grooves in the ears 41, wherefore in turn the side covers are firmly seated on the pins 27, 28. Thus the composite mask becomes a tightly united structure firmly seated on the carriage frame. The shroud normally covers certain mechanisms such as, for example, a tabulator rack bar 46 having settable stops 47 thereon. To gain access to such normally covered mechanisms, the shroud 21 may be forced rearwardly about the pivot studs 37. In doing this, the inclined tongues 45 force the ears 43 upwardly to by-pass them. Once the tongues 45 are free of the ears 43, the shroud 21 may be lifted off the pivot studs 37. Stop lugs 48 on the arms 42 are engageable with frame-projections 51 to limit downward movement of the arms when the tongues 45 clear the ears 43. As seen in Figures 1 and 3, the lugs 48 normally stand off the projections 51 so that normally the ears 43 bear effectively on the tongues 45. The front edges of the tongues 45 are so formed as to be capable of forcing the arms 42 upwardly when the shroud 21 is swung to masking position. As the shroud 21 nears masking position, the tongues pass in front of the ears 43 and draw the shroud forwardly and downwardly.

In the absence of an intermediate front masking member, it is desirable to steady the front ends of the side covers 18. To this end, a rubber collar 52 may be interposed between each frame end 12 and adjacent side cover 18 while screws 53 passing through the covers and the collars 52 may hold the side covers onto the frame ends 12.

In its masking position, the shroud 21 is blocked against upward movement by ledges 57 underlying the protuberances 41, see Figures 3 and 5. The shroud 21, therefore, cannot be re-

moved from the carriage unless it is first moved rearwardly about the pivot studs 37.

To insure against accidental dislodgement of the mask assembly from the carriage, each carriage end 12 may have a pin 54 laterally extending into a socket hole 55 on the adjacent side cover 18. Preferably, there is normally a clearance around the pin 54 so that, under ordinary circumstances, the pin 54 serves no function. However, it will be seen that the side covers 18 cannot be dislodged from the pivot pins 27, 28 as long as the shroud 21 is interlocked with the side covers.

When it is desired to remove either one or both of the side covers 18, the shroud 21 is first swung rearwardly and, if desired, removed. Either of the side covers, after loosening the screw 53, may then be swung outwardly free of the pin 54. The ears 25 and 26 being provided with open seats, allow then the removal of the outwardly swung cover from the machine.

In the aforementioned patent to Helmond No. 2,172,008, draw bolts 67 are provided which form part of a platen lock-down device. Corresponding draw bolts are numbered 56, in the present drawing, and protrude normally from the opposite carriage ends 12 through clearance holes provided in the side covers 18. It will be observed that the draw bolts remain on the carriage and that the side covers 18 are swung into position over them.

Figure 4 illustrates a slightly modified structure whereby a side cover 18 may be placed upon the carriage. The previously-described forked ear 25 and the pin 27 have been omitted, and the side cover is located on the carriage at its lower front by means of a pin 58 which projects from the carriage rail 13 into the side cover 18.

The carriage is shown to embody a paper table 40 61 which may be hingedly displaced for gaining access to adjustable margin stops 62.

While the form of the structure herein described is admirably adapted to fulfill the objects stated, it is to be understood that it is not intended to confine the invention to the form of embodiment herein described; for the invention obviously may take many forms, all coming within the purposes and scope of the present improvements.

50 What I claim is:

1. In a typewriting machine, a mechanism-supporting frame, two oppositely disposed masking members on said frame, an intermediate shrouding member, means for seating said intermediate shrouding member swingably for movement toward and away from said frame, to and from a shrouding position, said seating means being adapted to allow ready removal of the intermediate shrouding member, and interfitting means adapted to lock said oppositely disposed masking members firmly to said intermediate member when the latter is swung to its shrouding position.

2. In a typewriting machine, a mechanism-supporting frame, two oppositely disposed spaced masking members for said frame, means for removably and swingably seating said members in definitely spaced relation on said frame, an intermediate shroud, and means on said members and said shroud fitting each other in a manner so that said members and said shroud are normally interlocked in the direction in which the members are spaced, and so that the shroud is removable from said members.

3. In a typewriting machine, a mechanism-supporting frame, two oppositely disposed masking members for said frame, means for removably and swingably seating said masking members in spaced relation on the frame, an intermediate masking member, means rendering said intermediate member swingable to and from its masking position, and means adapted to lock said oppositely disposed members firmly to said intermediate masking member when the latter is swung to its masking position.

4. In a typewriting machine, a mechanism-covering mask comprising, two substantially parallelly spaced masking members, and an intermediate masking member, means adapting at least said intermediate member for swinging movement to and from a masking position, interfitting means adapted to lock said spaced members to said intermediate member when the latter is swung to its masking position, and means adapted to hold said intermediate member resiliently in masking position to maintain thereby a firm interlock at said interfitting means.

5. In a typewriting machine, two oppositely disposed, mechanism masking members, an intermediate shroud, means seating said shroud swingably for movement from and to a shrouding position, about an axis extending intermediate said masking members, said seating means comprising open pivoting seats rendering said shroud quickly placeable on or removable from the machine, interfitting means adapted to lock said oppositely disposed members to said shroud when the latter is swung to shrouding position, and means blocking said shroud against removal, except when said shroud is swung from shrouding position.

6. In a typewriting machine, a mechanism-supporting frame, two oppositely disposed spaced masking members for said frame, means rendering said members seatable on said frame, an intermediate shroud adapted to be placed on said members, means on said shroud and said members interlocking the members with the shroud in the direction in which the members are spaced, resilient means associated with the frame for forcing said shroud on said spaced members, said shroud being so placeable on said members, and said rendering means being so arranged with respect to said forcing means, as to enable said forcing means to exert normally a resilient seating force on said spaced members, and cooperative means on said frame and said members adapted to anchor said members unremovably to said frame as long as the members are interlocked with said shroud.

7. A mechanism-encasing composite mask for a typewriting machine carriage, comprising, opposite carriage end covers provided with shoulders extending toward each other, and an intermediate shrouding member, said intermediate shrouding member and said shoulders having tongue and groove formations fitting each other so as to lock said end covers laterally to said intermediate shrouding member and so as to render said shrouding member removable from said covers, and means including a leverage device to force said tongue and groove formations into firmly interlocked relation.

8. In a typewriting machine, a mechanism-encasing composite mask, comprising, oppositely disposed spaced walls provided with shoulders extending toward each other, and an intermediate shrouding member, said intermediate member and said shoulders having tongue and groove for-

mations fitting each other so as to interlock said spaced walls firmly with said intermediate member in the direction in which said walls are spaced and so as to render said shrouding member removable from said walls, and lever-means to force said tongue and groove formations into firmly interlocked relation.

9. In a typewriting machine, a composite mask comprising two spaced and an intermediate masking member, open pivot means for said intermediate masking member, rendering it swingable to and from masking position and also removable from the machine, said intermediate member, when in masking position, locking said spaced members to the intermediate masking member in the direction in which the spaced members are spaced, and resilient means to urge said intermediate member to masking position after partially moving it thereto, said last means being devised to allow said intermediate member to be freely removed from the machine after being swung from masking position.

10. In a typewriting machine, a mechanism-supporting frame, a composite mask for said frame, comprising a plurality of masking members, means rendering fewer than all said members seatable against said frame, means rendering the remainder of said members seatable against said said members in a manner so that the latter are adapted to be seated and held firmly against said frame by forcing and holding the remainder of said members seated against said fewer of said members, and means associated with the frame and said remainder of said members for forcing and holding said remainder of said members seated against said fewer members.

11. In a typewriting machine, a mechanism-supporting frame, a composite mask for said frame comprising a plurality of masking members, means rendering fewer than all said members seatable against said frame, means rendering the remainder of said members seatable against said said members in a manner so that the latter are adapted to be seated and held firmly against said frame by forcing and holding the remainder of said members seated against said fewer of said members, and means associated with the frame and said remainder of said members, said last means including a resilient element for forcing and holding said remainder of said members seated against said fewer of said members.

12. In a typewriting machine, a mechanism-supporting frame, a composite mask for said frame, comprising two spaced and an intermediate masking member, means rendering said spaced members seatable against said frame, means rendering said intermediate member seatable against said spaced members in a manner so that the spaced members are adapted to be firmly seated and held against said frame by forcing and holding said intermediate member seated against said spaced members, and means associated with the frame and said remainder of said members for forcing and holding said intermediate member seated against said spaced members.

13. In a typewriting machine, a mechanism-supporting frame, two spaced masking members for said frame, means for seating said members at definitely spaced locations against the frame, an intermediate masking member, means oppositely on said intermediate member and said spaced members rendering the intermediate mem-

ber removably seatable against said spaced members, and including means to interlock the intermediate member with said spaced members in the direction in which the latter are spaced, said intermediate member being so seatable against the spaced members that the latter are adapted to be seated and held firmly against said frame,

5 by forcing and holding said intermediate member firmly seated against said spaced member, and means associated with the frame and said remainder of said members for forcing and holding said intermediate member firmly seated against said spaced member.

WILLIAM F. HELMOND.
